UNITED STATES PATENT OFFICE.

ALFRED T. JESTER, OF HOUSTON, TEXAS.

TELEGRAPH REPEATING SYSTEM.

1,116,591.

Specification of Letters Patent. Patented Nov. 10, 1914.

Application filed May 12, 1913. Serial No. 767,080.

To all whom it may concern:

Be it known that I, ALFRED T. JESTER, a citizen of the United States, residing at Houston, in the county of Harris and State 5 of Texas, have invented a certain new and useful Improvement in Telegraph Repeating Systems, of which the following is a full, clear, concise, and exact description, reference being had to the accompanying 10 drawings, forming a part of this specification.

My invention relates to telegraph repeaters and has for its object the provision of an improved repeater adapted to repeat both 15 ways.

More particularly my invention contemplates the provision of a repeating device having a plurality of electromagnetic elements, each such element having a plurality 20 of coils so arranged that one of the coils of each element when energized will attract the armature of its element, having however such a high resistance that the current necessary for the energization of this coil will 25 not be sufficient to attract or operatively energize any of the relay sounders on the telegraph line. Each electromagnetic element then also has a further winding, which winding is under the control of the sending 30 keys, and which winding when energized serving to attract the armature of the combined electromagnetic element to thereby retransmit the impulses toward the other end of the line.

I will explain my invention more in detail 35 by referring to the accompanying drawing setting forth two forms of carrying out my invention, in which—

Figure 1 is a diagrammatic representation 40 of my improved repeater showing its association with a telegraph line, and Fig. 2 is a modified form of the repeater circuit arrangement.

Referring more particularly to Fig. 1, I 45 show a repeating station A as adapted to repeat messages between two oppositely extending telegraph lines 1 and 2, respectively, which telegraph lines of course are provided with a plurality of the ordinary 50 series telegraph sets, one station only for each line however being shown, respectively B and C, which serve to indicate the character of the apparatus at each of such ordinary telegraph stations. The telegraph line.

1 is provided with the ordinary telegraph 55 relay 3 which controls the customary sounder, not shown, the sending key 4, and the short circuiting switch 5, this line being grounded at its extremity at 6. The telegraph line 2 is provided with similar apparatus consisting of the relay 7, the short circuiting switch 8, sending key 9, and is grounded at 10. At the repeating station I have two electromagnets respectively 11 and 12, the electromagnet 11 being provided 60 with a coil 13 and a coil 14, and the electromagnet 12 being provided with a coil 15 and a coil 16. The electro-magnets 11 and 12 are provided with armatures 17 and 18 respectively under the control of the ordinary 65 retractile springs 19. Back stops 20 are provided and front contacts 21 and 22 respectively. Batteries 23 and 24 have one terminal grounded and their other terminals connected respectively to the armatures 17 and 18. The telegraph lines 1 and 2 extend respectively to connecting points 25 from which they are continued through the windings of the electromagnets 11 and 12 respectively. The free terminal of the 70 winding 16 extends by means of the conductor 26 to the front contact 21 and the free terminal of the winding 14 extends by means of the conductor 27 to the front contact 22. The free terminals of the windings 13 and 15 extend by means of conductors 28 and 29 respectively to the respective armatures of their electromagnets. The resistance of the windings 13 and 15 is such that when for instance the short 75 circuiting switch 8 at station C is closed, that the current traveling through this winding 15, for instance, is sufficient to energize the electromagnet 12 to attract its armature 18, but insufficient to operatively 80 energize the relays 7. If the short circuiting switch is open, as for instance shown at station B, so that the circuit through the line wire 1 is open, then of course no current passes through the winding 13 and the 85 armature 17 remains unenergized. Assume then that the station B is intending to send signals, the short circuiting switch 5 is opened but of course the short circuiting switch 8 of the line wire 2 is closed because 90 that line wire is receiving. The circuit through the coil 15 then is closed from the ground 10, short circuiting switch 8, relay 95

7, line wire 2, coil 15, conductor 29, battery 24 to ground 30. This current, while it is sufficient to energize the winding 15, is insufficient to actuate the relay 7. The attraction of the armature 18 however has completed the circuit from the ground 30, through battery 24, armature 18, front contact 22, conductor 27, coil 14, to line wire 1, and from there through the sending key 4 to ground at 6 so that when the sending key 4 is actuated it energizes the winding 14 to thereby attract its armature 17 to thereby close a circuit from ground 31 through battery 23, armature 17, contact 21, conductor 26, winding 16, line wire 2, through the telegraph sets of line wire 2 to ground at 10. In this manner the signals are repeated at the station A. The same action takes place but in a reverse order when station C is 20 communicating to station B. The windings 13 and 14 as likewise the windings 15 and 16 are wound cumulatively. The winding 16 is of the ordinary resistance of the regular telegraph relay. From this it is 25 thought the operation of my improved repeater will be entirely clear.

In Fig. 2, I have set forth a modification in which the free terminals of the windings 13 and 15 respectively are led by conductors 30 32 and 33 respectively to the armatures 18 and 17 of the combined electromagnets so that both batteries 23 and 24 come into play during the signaling operation.

While I have herein shown and particularly described two embodiments of my invention, I do not mean to limit myself to such description and illustration, but

Having thus described how my invention can be carried out, what I claim as new and 40 desire to secure by Letters Patent is:

1. A telegraph repeating system consisting of two telegraph lines, an electromagnetic device for each line, each having two coils and an armature, the electromagnetic device for one line when actuated actuating its armature to establish a circuit to repeat impulses to the other telegraph line through one coil only of the electromagnetic device of said other telegraph line, the other coil 45 of said last electromagnetic device serving for relay energizing purposes and being associated electrically with the telegraph line.

2. A telegraph repeating system consisting of two telegraph lines, an electromagnetic device for each line, each having two coils and an armature, the electromagnetic device for one line when actuated actuating its armature to establish a circuit to repeat impulses to the other telegraph line through 50 one coil only of the electromagnetic device of said other telegraph line, the other coil of said last electromagnetic device serving for relay energizing purposes and being associated electrically with the telegraph line.

3. A telegraph repeating system consisting

of two telegraph lines, an electromagnetic device for each line having two coils, the electromagnetic device for one line having an armature to repeat impulses to the other telegraph line through a winding of the electromagnetic device of said other telegraph line, one of the windings of each electromagnetic device having a resistance sufficient to prevent energization of telegraph relays of its associated line, but sufficient ampere turns 70 to attract its associated armature with such energization.

4. A telegraph repeating system consisting of two telegraph lines, an electromagnetic device for each line having two coils, 80 the electromagnetic device for each line having an armature to repeat impulses to the other telegraph line through a winding of the electromagnetic device of said other telegraph line, and a battery for each line, one of the windings of each electromagnetic device having a resistance sufficient to prevent energization of telegraph relays of its associated line, but sufficient ampere turns to 85 attract its associated armature with such energization.

5. A telegraph repeating system consisting of two telegraph lines, an electromagnetic device for each line having two coils, the electromagnetic device for one line having an armature to repeat impulses to the other telegraph line through a winding of the electromagnetic device of said other telegraph line, one of the windings of each electromagnetic device having a resistance sufficient to 95 prevent energization of telegraph relays of its associated line, but sufficient ampere turns to attract its associated armature with such energization, each electromagnetic device having an armature and a front contact, said front contact being connected to a terminal of the second winding of each electromagnetic device.

6. A telegraph repeating system consisting of two telegraph lines, an electromagnetic device for each line having two coils, the electromagnetic device for each line having an armature to repeat impulses to the other telegraph line through a winding of the electromagnetic device of said other telegraph line, and a battery for each line, one of the windings of each electromagnetic device having a resistance sufficient to prevent energization of telegraph relays of its associated line, but sufficient ampere turns 110 to attract its associated armature with such energization, each electromagnetic device having an armature and a front contact, said front contact being connected to a terminal of the second winding of each electromagnetic device.

7. A telegraph repeating system consisting of two telegraph lines, an electromagnetic device for each line, each having two coils and an armature, the electromagnetic 120

device for one line when actuated actuating its armature to establish a circuit to repeat impulses to the other telegraph line through one coil only, and the armature of the electromagnetic device of said other telegraph line, the other coil of said last mentioned electromagnetic device receiving its current over a telegraph line aforesaid serving to

maintain its associated armature in an attracted position.

In witness whereof, I hereunto subscribe my name this 3d day of May, A. D. 1913.

ALFRED T. JESTER.
